UNITED STATES PATENT OFFICE.

ARTHUR F. CONERY, JR., OF NEWARK, NEW JERSEY.

DESIGN FOR A RECEPTACLE-CAP.

No. 38,207.

Specification for Design.

Patented Aug. 28, 1906.

Application filed June 4, 1906. Serial No. 320,212. Term of patent 7 years.

To all whom it may concern:

Be it known that I, ARTHUR F. CONERY, Jr., a citizen of the United States, residing in Newark, in the county of Essex and State of New Jersey, have invented a new, original, and ornamental Design for Receptacle-Caps, of which the following is a specification, reference being had to the accompanying drawings, forming a part thereof.

The accompanying drawings show, in Fig-

ure 1, a side view of a receptacle-cap embodying my design; in Fig. 2, a bottom view of the same, and in Fig. 3 an end view of the same.

I claim—

The ornamental design for a receptacle-cap, as shown.
